Atty.

UNITED STATES PATENT OFFICE.

LEWIS WATSON EGGLESTON, OF APPLETON, WISCONSIN.

VENTING-VALVE FOR RADIATORS.

No. 866,845.

Specification of Letters Patent.

Patented Sept. 17, 1907.

Application filed January 19, 1907. Serial No. 353,099.

To all whom it may concern:

Be it known that I, LEWIS WATSON EGGLESTON, a citizen of the United States, and a resident of Appleton, in the county of Outagamie and State of Wisconsin,

5 have invented certain new and useful Improvements in Venting-Valves for Radiators, of which the following, when taken in connection with the drawing accompanying and forming a part hereof, is a full and complete specification, sufficient to enable those skilled 10 in the art to which it pertains to understand, make, and use the same.

This invention relates to valves attached to radiators, to automatically vent such radiators of the air which, at times, collects therein, without permitting water or 15 steam to flow from the radiator therethrough.

The device illustrated by the drawing referred to is particularly applicable to hot water radiators; and the object of the invention is to obtain a venting valve which will be economical in construction; simple in 20 arrangement of parts and not liable to get out of order; which will not permit leakage of water therethrough and will permit the placing of a top or slab on the radiator to extend over the ends thereof without removal of the valve therefrom.

25 Figure 1 of the drawing is an elevation of a portion of the upper part of the end sections of a hot water radiator, with a device embodying this invention attached thereto, such device showing in end elevation. Fig. 2 is a front elevation, on an enlarged scale from 30 Fig. 1, of a device embodying this invention. Fig. 3 is a longitudinal section on line 3—3 of Fig. 1, viewed in the direction indicated by the arrows. Fig. 4 is a transverse section on lines 4—4 of Fig. 2, viewed in the direction indicated by the arrows. Fig. 5 is a 35 side elevation, on a scale enlarged from Figs. 1 to 4 inclusive, of the valve and valve stem of the device, Fig. 6 is a top plan of the valve and valve stem of the device on the same scale as such valve and stem are shown in Fig. 5. And Fig. 7 is a fragmentary longitudinal section of a modified construction of a device 40 embodying this invention.

A reference letter applied to designate a given part is used to indicate such part throughout the several figures of the drawing wherever the same appears.

45 A is a radiator member.

B is the shell of the apparatus embodying this invention, such shell comprising a cylindrical portion and the ends b, b'. Such ends and cylindrical portion are, of course, secured together so that there will 50 be no leakage of air, water or steam at the junction thereof from the shell B.

C is the stem of the shell B and is screw threaded in the ordinary way to engage with corresponding threads and form the means of attachment of the device to a radiator member. The stem C is provided 55 with passage way D therethrough, such passage way,

when the device is attached to a radiator member, communicating with the interior of the radiator and with float chamber E in shell B to form the inlet to such chamber.

60

F is the outlet of chamber E.

G is a float provided with projections H, h, and I, I.

J is an arm which I prefer to rigidly attach to end b of the shell. Arm J may be provided with an aperture near one end thereof through which aperture the projection H extends when the several parts forming the device are assembled and such arm J and projection H form the fulcrum on which the float G rocks as the end g of such float rises as the chamber E is partially filled with water flowing thereinto from the radiator through 70 the inlet D.

K is a valve stem provided at one end thereof with aperture k, and at the other end with valve k'. Projection h on float G extends through hole or aperture k on valve stem K when the several parts of the device 75 are assembled, and when the end g of the float G is raised by water in chamber E of the shell the valve k' is forced longitudinally forward on to the seat f of outlet F, to close such outlet. In Fig. 3 float G is shown with end g about midway of its upward travel, 80 at which time valve k' is nearly seated to close the outlet.

Projections I, I, serve as guides to limit the side or rolling movement of float G as it rocks on its fulcrum on opening and closing the outlet F. The specific gravity 85 of the float between the fulcrum point thereof and end g is considerably less than that of water or of condensation, while the specific gravity of end g' thereof is considerably greater than that of water or of condensation, so that the float is easily rocked on its fulcrum to seat the valve k' by water entering the float chamber through the inlet thereof, and but little water is required therefor in such chamber E. By constructing the two ends of the float of different specific gravities quick closing of the valve on the 95 valve seat of the outlet is obtained, and after the water has closed the valve to its seat additional water in the float chamber exerts additional pressure on the seated valve. By placing the valve stem K, in a substantially horizontal plane as shown, with one end thereof 100 supported on the float G, at a point substantially over the fulcrum of the float, the weight of the valve stem imposes no substantial obstruction to the movement of the float. By the closing of the valve on its seat in this manner and the holding it to its seat as shown it 105 occurs that even if the float chamber is completely filled with water there is no leakage thereof through the outlet.

The cylinder of the shell B being horizontal and the outlet F being placed at the end thereof, all as shown, 110 no portion of the device comes above the top of the radiator members, and hence a shelf or other article

may be placed on the top of the radiator and extend beyond the ends thereof without requiring the removal of the valve therefrom.

By reference to Fig. 3 it will be seen that all the operative parts of the valve are mounted on end b' when the parts of the valve are assembled, and that thereafter such end b' may be put into place in the end of the cylindrical portion of the shell and secured. The projection H may be made so long that it comes in contact with the bottom of the shell B , so that the float turns on such projection H , if preferred, in which case bar J is a guide for such projection H . This construction is illustrated in Fig. 7, of the drawing.

Having thus described my invention what I claim is new and desire to secure by Letters Patent is;—

1. In a venting valve for radiators, a shell consisting of end and connecting side walls, and provided with a float chamber and an inlet and outlet to the chamber, such outlet located in one of the end walls of the shell and provided with a valve seat and such inlet arranged to discharge into the float chamber near the bottom thereof, in combination with a float, a fulcrum located between the ends of the float and such float movable on the fulcrum, a valve stem provided with a valve arranged to co-act with the valve seat, and a supporting connection between the valve stem and the float the several parts being so associated that the point of support of the valve stem upon the float is substantially over the fulcrum; substantially as described.
2. In a venting valve for radiators, a shell consisting of a cylindrical portion having closed ends, and provided with a float chamber and an inlet and outlet to the chamber, such outlet provided with a valve seat and such inlet arranged to discharge into the float chamber near the bottom thereof when the axis of the cylindrical portion of the shell is in a horizontal plane, in combination with a float, a fulcrum located underneath the float and such float movable on the fulcrum, the specific gravity of the float on one side of a vertical plane extending through the fulcrum greater than the specific gravity of the float on the other side of such vertical plane, a valve stem provided with a valve arranged to co-act with the valve seat, and a supporting connection between the valve stem and the float such connection located substantially over the fulcrum, of the float; substantially as described.
3. In a venting valve for radiators, a shell consisting of a cylindrical portion having closed ends, and provided with a float chamber and an inlet and outlet to the cham-

ber, such outlet provided with a valve seat and such inlet arranged to discharge into the float chamber near the bottom thereof when the axis of the cylindrical portion of the shell is in a horizontal plane, in combination with a float, a bar rigidly attached to one end of the shell, such bar provided with an aperture therein, a projection on the float between the ends thereof, such projection fitting loosely in the aperture in the bar, to form the fulcrum of the float, such float constructed so that the specific gravity on one side of a vertical plane extending through the fulcrum and float is greater than the specific gravity thereof on the other side of such vertical plane, a valve stem provided with a valve arranged to co-act with the valve seat, and a supporting connection between the valve stem and the float such connection located substantially over the fulcrum of the float; substantially as described.

4. In a venting valve for radiators a shell provided with end and side walls and with a float chamber having an inlet and an outlet, such outlet located in an end wall, and provided with a valve seat and such inlet located in the side wall of the shell and arranged to discharge into the float chamber near the bottom thereof, in combination with a float, a valve stem provided with a valve arranged to co-act with the valve seat of the outlet, a supporting connection between the valve stem and the float, such connection located substantially over the fulcrum of the float, and a fulcrum located underneath the float and between the ends thereof, such float movable on the fulcrum and a guide to such fulcrum mounted on the end wall in which the outlet is placed; substantially as described.

5. In a venting valve for radiators a shell consisting of end and connecting walls, such shell provided with a float chamber having an inlet and an outlet, such outlet located in one of the ends of the shell and provided with a valve seat and such inlet arranged to discharge into the float chamber near the bottom thereof, in combination with a float, a valve stem provided with a valve arranged to co-act with the valve seat of the outlet, a supporting connection between the valve stem and the float, such valve stem and float arranged so that one end of the valve stem rests on the float and operatively associated so that the end of the valve stem which is adjacent to the float is substantially over the fulcrum thereof and not appreciably raised by the movement of such float, and a fulcrum located underneath the float and between the ends thereof; substantially as described.

Signed at Chicago, Ill., this 17th day of January, 1907.
LEWIS WATSON EGGLESTON.

In presence of—

CHARLES TURNER BROWN,
CORA A. ADAMS.
